DESIGN FOR A BOTTLE

Donald Deskey, New York, N. Y., assignor to Northam Warren Corporation, Stamford, Conn.,
a corporation of New York

Application September 23, 1940, Serial No. 95,295

Term of patent 14 years

To all whom it may concern:

Be it known that I, Donald Deskey, a citizen of the United States, residing at 1070 Park Avenue, New York city, in the county of New York and State of New York, have invented a new, original, and ornamental Design for a Bottle, of which the following is a specification, reference being had to the accompanying drawing, forming part thereof.

In the drawing

Fig. 1 is a front elevational view of a bottle showing my new design.

Fig. 2 is a side elevational view thereof.

Fig. 3 is a top plan view.

Fig. 4 is a sectional view on line 4—4 of Fig. 1.

Fig. 5 is a sectional view on line 5—5 of Fig. 1.

I claim:

The ornamental design for a bottle, as shown.

DONALD DESKEY.
